UNITED STATES PATENT OFFICE

155,724

DESIGN FOR A SMOKING STAND

Joseph S. McInnis, Chicago, Ill., assignor to Metallic Arts Corporation, Chicago, Ill., a corporation of Illinois

Application March 25, 1949, Serial No. 1,607

Term of patent 14 years

(Cl. D85—2)

To all whom it may concern:

Be it known that I, Joseph S. McInnis, a citizen of the United States and resident of Chicago, in the county of Cook and State of Illinois, have invented a new, original, and ornamental Design for a Smoking Stand, of which the following is a specification, reference being had to the accompanying drawing, forming a part thereof.

The drawing illustrates a perspective view of a smoking stand showing my new design.

I claim:

The ornamental design for a smoking stand, substantially as shown.

JOSEPH S. McINNIS.
